UNITED STATES PATENT OFFICE.

FENTON WRIGHT, OF CHICAGO, ILLINOIS.

COIN-ACTUATING SAVINGS-BANK.

1,139,006.

Specification of Letters Patent. Patented May 11, 1915.

Application filed May 8, 1912. Serial No. 695,957.

To all whom it may concern:

Be it known that I, FENTON WRIGHT, citizen of the United States, residing at Chicago, in the county of Cook and State 5 of Illinois, have invented certain new and useful Improvements in Coin-Actuating Savings-Banks, of which the following is a specification.

My invention relates to new and useful 10 improvements in coin banks, and the object of my invention is to provide a coin bank having a clock, preferably an alarm clock, mounted in its upper portion.

A further object of my invention is to 15 so position the clock and to so form the casing of the bank that under normal conditions access to the clock, for the purpose of winding the clock or alarm or setting the clock or alarm, is prevented.

20 A further object of my invention is to provide coin controlled means by which the insertion of a coin in the coin receiving slot of the bank and the proper manipulation of a plunger will permit access to the winding 25 and setting mechanism of the clock.

A further object of my invention is to provide means for maintaining the coin 30 actuated mechanism in position during the winding or setting of the clock.

35 A further object of my invention is to provide means for automatically returning the coin controlled mechanism to normal position upon the release of the plunger and so prevent further access to the clock until the insertion of another coin.

40 A further object of my invention is to provide a removable inner casing or coin receptacle forming the bottom or lower end of the bank. And a still further object of my 45 invention is to provide a novel means for locking the removable casing in place.

With these and other objects in view, my 50 invention will be more fully described, illustrated in the accompanying drawings, and then specifically pointed out in the claims which are attached to and form a part of this application.

55 In the drawings: Figure 1 is a central vertical section on the line 1—1 of Fig. 2, the clock being removed to permit the clear showing of the coin actuated mechanism; Fig. 2 is a vertical section on the line 2—2 of Fig. 1, showing further details of the coin actuated mechanism; Fig. 3 is a vertical section on the line 3—3 of Fig. 1 upon an enlarged scale and showing the opera-

tion of the plunger; Fig. 4 is a transverse section on the line 4—4 of Fig. 1, still further disclosing the position and operation of the coin actuated mechanism; Fig. 5 is a perspective of the upper and lower plates employed in forming the casing for the clock and coin controlled mechanism; Fig. 6 is a perspective of the lower side of the lowermost of these plates, showing the 60 spring pressed closure for preventing the return of the coins contained in the coin receptacle; Fig. 7 is a perspective of the auxiliary back plate and the shoulders carried thereby and forming a chute for the 65 coin, the plunger which co-acts with these shoulders in forming the chute being shown detached; Fig. 8 is a top plan view of the removable lower casing or coin receptacle, showing the manner of operating the lock; 70 Fig. 9 is a fragmentary perspective of the key employed in unlocking the lock; Fig. 10 is a section on the line 10—10 of Fig. 1, showing certain details of the lock structure. 75

Corresponding and like parts are referred 80 to in the following description and indicated in all the views of the drawings by the same reference characters.

The preferred embodiment of my invention includes an outer casing 10, preferably 85 rectangular in shape and formed of metal, this casing being closed at its upper end by an integrally formed top 11 and provided in its forward face with a circular aperture 12 in which is mounted a glass plate 13, through 90 which the face of the clock is exposed, as will be hereinafter explained. Supported within the upper portion of this casing and in parallel spaced relation to the top thereof, is a metallic plate 14 forming the top of an 95 inner casing, the bottom of which is formed by a second plate 15 and the side and end walls of which are formed by the corresponding walls of the casing proper of the bank. The upper plate 14 is supported in 100 position by means of a plurality of tie bolts 16 and nuts 17, while the lower plate is supported in proper spaced relation to the upper plate by similar tie bolts 18 and nuts 19.

The lower end of the casing 10 is closed by 105 a removable casing 20 which forms the coin receptacle of the bank and which includes a bottom 21 and vertically extending walls 22. This removable casing is proportioned to fit closely within the main or outer casing, as 110 best shown in Figs. 1 and 2 of the drawings and secured to the inner faces of the end

walls of the removable casing, are leaf springs 23 which extend vertically of the casing and the upper ends of which terminate adjacent the upper ends of the walls of the inner casing in outwardly directed hooked terminals 24 having their outer upper portions beveled as shown at 25 for movement over the inner, lower beveled faces 26 of the hooked terminals 27 carried by L-shaped arms 28 secured to the end portions of the lower plate 15. As best shown in Fig. 1, the upper portions of the end walls of the inner casing are slotted as at 29 to receive the hooks 27 when the removable casing is in place.

As will be readily apparent, the insertion of the removable casing 20 in the lower end of the main casing 10 completely closes the main casing and the interengagement between the hooks 24 and 27 absolutely locks the removable casing against disengagement.

As a means for releasing the removable casing and removing the same, I have provided its bottom wall 21 with a centrally formed opening 30 and surrounding this opening and extending vertically upward within the removable casing, is a cylindrical casing 31 which is open at both ends and which terminates slightly below the upper end of the removable casing. Mounted in the upper end of this cylindrical casing 31, is the mechanism for releasing the hooks 24 from their engagement with the hooks 27. This mechanism includes a cylindrical body member 32 fitted closely within the upper end of the casing 31 and provided with a centrally formed longitudinal bore 33, counterbored at its upper end to form an annular shoulder 34 and provided adjacent its lower end with an annular groove 35 forming a shoulder 36. Positioned within the bore of this body member, is a post 37 having a shoulder 38 which engages with the shoulder 34 of the body member 32 and terminating at its upper end in a circular head 39 which bears upon the upper end of the casing 31. The post 37 is provided adjacent its upper end with an annular groove 40 and the body member 32 is supported in the upper end of the casing 31 by a split pin 41 which is passed through aligned perforations formed in the wall of the casing 31 and the wall of the body member 32 and the central portion of which seats in the groove 40 of the post 37. As will be seen, the passing of this pin through the body member and its casing serves to hold the body member against movement of any kind in the casing, while its seating in the groove of the post prevents the upward movement of the post, while at the same time permitting its free rotation of the body member.

Threaded or otherwise secured in the upper face of the head 39, are diametrically disposed pivot pins 42 and secured by their

inner ends to these pivot pins, are arms 43, the free ends of which are provided with downwardly directed hooked terminals 44 adapted to engage in openings formed in the laterally directed arms 45 of L-shaped plates 46 which are carried by the upper ends of the springs 23.

As will be apparent from the foregoing description, a rotation of the post 37 will act through the eccentrically positioned pivots 42 and the arms 43 to draw the upper ends of the springs 23 inwardly and so release their hooked terminals from the hooks 27 and permit the withdrawal of the removable casing. As a means for rotating the post 37, I have provided its lower end with a reduced extension 47 which, as best shown in Fig. 10, is formed with angular faces adapted to seat in a correspondingly formed socket 48 in the terminal of a key shank 49 which, in operation, is passed upwardly through the opening 30 in the bottom of the casing 20. As best shown in Fig. 9 of the drawings, the free end of this key shank is provided with a longitudinally extending slot 50 having a laterally directed terminal 51 and, as will be seen by referring to Fig. 1 of the drawings, the body member 32 is provided with an inwardly directed pin 52 adapted to pass into the slot 50 of the key 49 when the latter is applied to the reduced end of the post and to pass into the extension 51 of the key when the latter is turned to release the hooks. By this means the turning of the key prevents its disengagement from the post and a downward pull upon the key will consequently draw the removable casing out of the main casing in case of any binding or catching between their walls.

As a means for preventing any unauthorized removal of the casing 20 or coin receptacle, I preferably provide a plug lock 53 which is mounted in a cylindrical casing 54 proportioned to seat in and close the open lower end of the cylindrical casing 31. The lower end of this casing 54 is closed with the exception of a key receiving opening 55 and is provided at one side with a laterally directed extension 56 which seats in a correspondingly formed recess 57 in the bottom wall 21 of the removable casing and which prevents rotation of the lock casing within the casing 31 upon the turning of a key inserted into the lock through the opening 55. This plug lock consists primarily of a pivoted lock bar 58, the upper end of which is provided with a hooked terminal 59 adapted to engage the interiorly formed shoulder 36 of the body member 32, while the lower end bears against the tumblers 60. The lever 58 is pivotally mounted upon a pin 61 which passes through spaced shoulders 62 formed upon the inner wall of the lock casing and is normally held in operative position by

means of a helical spring 63 which bears between the lock casing and the rear face of the lever 58. This spring is held against disengagement by a pin 64 which is secured by one end to the lock casing and the other end of which passes through a perforated plate 65 movable over the back face of the lever 58 and through a slot 66 formed in the lever. When this plug lock is applied all access to the coin receptacle of the bank, by any one not having the proper key, is prevented and the provision of this auxiliary lock therefore prevents the necessity of the owner carrying around the key 49 previously described, which must, of necessity, be comparatively large. It also serves as an added lock as it is practically an absolute necessity to have both keys to open the bank, the pin 52 not only performing the function previously described, but also preventing the application of any ordinary form of socket key.

The mechanism whereby the inner casing is locked in engagement with the outer casing by the key-actuated mechanism heretofore described, forms the subject of a divisional application for patent filed by me on the 18th day of September, 1912, Serial No. 721,032.

Secured upon the upper face of the lower plate 15, are spaced brackets 67 to which is secured the alarm clock which may be of any preferred type and which is shown conventionally at 68. This alarm clock is provided with the customary levers 69 and 70 for cutting off the alarm mechanism and for regulating its time mechanism, the free ends of these levers extending through suitable slots 71 and 72, respectively, formed in the rear wall of the casing 10. The clock also has the customary key posts 73 and 74 for the reception of a key for winding the clock and for winding the alarm and the key posts 75 and 76 for setting the alarm and setting the clock. The rear wall of the casing 10 is provided with suitable openings in alignment with these posts to permit the passage of a key for winding and setting the clock and alarm.

Secured between the side walls of the casing 10 and between the plates 14 and 15 and in parallel spaced relation to the back wall of the casing, is a plate 77 which is provided with openings 78, 79, 80 and 81 corresponding to the key posts 73, 74, 75 and 76, and consequently in alignment with the openings formed in the rear wall of the casing. The upper corners of this plate are cut-away as at 82 to permit the fitting of the plate about the bolts 19 and the upper and lower edges of the plate are cut-away centrally as at 83 and 84 for the passage of the levers 69 and 70.

The forward face of the plate 77 is provided with a plurality of laterally directed

ribs defining a coin chute and including parallel spaced apart diagonal ribs 85 and vertically extending spaced apart ribs 86 and 87, the latter of which is broken away as shown at 88, while the former is provided with an overhanging shoulder 89 which projects toward the rib 87 and in parallel spaced relation to the plate 77. The free ends of the ribs 85 bear against one of the side walls of the casing 10 and said wall is provided with a coin receiving slot 90, through which a coin may be passed to the chute. The free ends of the ribs 86 and 87 terminate flush with the lower edge of the plate 77 and the plate 15 is provided with a slot 91 through which the coin may pass from the chute to the coin receptacle.

As a means for preventing the escape of the coin from the chute into the compartment occupied by the clock, and for other purposes which will be hereinafter explained, I have provided a carriage or plunger 92 including a substantially rectangular shaped plate of metal which bears against the ribs forming the slot, as shown in dotted lines in Fig. 1 and in full lines in Figs. 2, 3 and 4. One edge of this plate is slotted and bent over to form a shoulder 93 and this edge is seated beneath the shoulder 89 of the rib 86, the shoulder 93 serving to maintain the plunger in proper spaced relation with respect to the plate 77. The plunger is provided adjacent its upper end with a forwardly directed arm 94 to which is secured one end of a guide pin 95 which extends in parallel spaced relation to the body of the plunger 92 and the lower end of which is movable through an opening 96 formed in the plate 15 and adjacent the slot 91 through which the lower end of the plunger body itself is movable, this lower end being preferably bifurcated as shown at 97. A helical spring 98 surrounds this pin 95 and bears between the arm 94 and the plate 15 to normally maintain the plunger in raised position. The inner edge of the plunger is provided at its upper end with a rearwardly directed extension 99 which bears against the outer face of the rib 87 and the purpose of which will be hereinafter explained. The rear face of the plunger is formed with a rearwardly directed stud 100 which is movable in a vertical slot 101 formed in the plate 77 and which has its opposite sides parallel to prevent any swinging movement of the plunger. The rear wall of the casing 10 is provided with a vertically extending slot 102 through which is passed the shank 103 of a thumb screw 104, the free end of the shank being threaded into a suitable socket formed in the stud 100.

As will be readily seen, the plunger may be forced downwardly against the action of the spring 98 by pressure applied upon the 129

head of this thumb screw. A plate 105 is preferably interposed between the head of the thumb screw and the rear wall of the casing, said plate being provided with a 5 perforation through which the shank 103 passes, and this plate is movable with the thumb screw and serves to close the slot 102 irrespective of the position of the plunger and so prevent the insertion of a wire or 10 other device to the coin actuated mechanism.

The plate 77 is provided directly above the openings 80 and 81 with a forwardly directed pin 106 which passes through a slot 107 formed in a bar 108, both edges of which 15 are provided with rack teeth 109. The lower end of this bar terminates, as shown, immediately above the lever arm 70 and the bar is provided intermediate its length with spaced openings 111 and 112 which, in one 20 position of the bar, register with the openings 80 and 81, respectively, of the plate 77. The upper end of the bar is provided with oppositely directed arms 113 and a plate 114 carried by the plate 14 has downwardly 25 directed pins 115, the free ends of which pass through suitable openings in the ends of the arms 113. The bar is normally maintained in its lower position by helical springs 117 which surround the pins 115 and which 30 bear between the arms 113 and the plate 114.

Pivottally mounted upon bolts or rivets 118 and maintained in spaced relation from the plate 77 by collars 119, are gears 120 and 123 which mesh with the teeth of the 35 rack bar. The gear 120 is provided with an opening 122 which registers with the opening 78 when the gear has been turned by the raising of the rack bar and the gear 123 is provided with an opening 124 which registers with the opening 79 when the gear 123 40 has been turned to raise the rack bar to bring its openings into registration with the openings 80 and 81 of the plate 77.

As best shown in Fig. 1 of the drawings, 45 the teeth of the gear 123 are omitted throughout a portion of its circumference and a portion of the gear extends through the space 88 formed in the shoulder 87 and so in the path of the coin during its passage 50 through its chute. The chute and gears are so proportioned that when the toothless portion of the gear 123 is presented through the opening 88, sufficient space is left for the passage of the coin through the chute, while 55 when a toothed portion projects into the chute, the coin is engaged by the teeth and prevented from further movement. Under normal circumstances, the gear 123 has a portion of its teeth positioned in the path 60 of a coin as shown in Fig. 1.

When a coin is dropped through the slot 90 it passes through the chute until stopped by the teeth of the gear 123, in which position it is immediately below the stud 100 of 65 the plunger 92. The plunger 92 is then

moved downwardly and its stud engaging the upper edge of the coin forces the same downwardly between the gear 123 and the opposite side of the chute causing the gear 123 to rotate until its opening 124 is in 70 alignment with the opening 79 of the plate 77 when, as previously described, the opening of the gear 120 and the openings of the rack bar are in alignment with their corresponding openings in the plate. When the 75 gear has been so rotated, its un toothed portion alone extends within the chute and the coin being no longer blocked in its passage falls through the slot 91 to the coin receptacle. 80

In order to prevent the immediate return of the gears and rack bar to normal position upon the release of the coin, I have provided the gear 123 with a notch 125 which, in operative position of the gears and in lowered 85 position of the plunger, receives the rearwardly extended arm 99 of the plunger which consequently holds the gear against counter-rotation until the plunger is released. The gear 123 is also provided adjacent this notch with a shoulder 126 which, in operative position of the gear, engages against a portion of the rib 87 to prevent 90 over-rotation of the gear.

As a means for preventing the return of 95 the coins from the coin receptacle through the slot 91 by the inverting of the bank, I have provided a plate 127, one end of which is bifurcated to form tongues 128 which are rolled about a pivot pin 129 carried by the 100 lower face of the plate 15 to form a hinge connection. This plate is normally held in raised position against the lower face of the plate 15 by a spring 130, one end of which is passed beneath the adjacent arm 28 and 105 the other end of which is passed through a perforation of the tongue 131 formed integrally with the free end of the plate in the manner shown.

Upon the depression of the plunger to 110 force the coin through the chute, the lower end of the guide pin 95 passes through its opening 96 formed in the plate 15 and engages against the upper face of the hinged plate 127 to swing the same away from the 115 slot 91 and permit the free passage of the coin.

From the foregoing description, the use 120 and operation of my combined coin bank and clock will be readily understood. When access to the clock is necessary, either for winding the clock or alarm or for setting the clock or alarm, or for both, a coin is inserted 125 in the slot 90 and passes through the chute until stopped by the gear 123. The plunger 125 is then forced downwardly to force the coin by the gear, the gear being rotated in the meantime to raise the rack bar, and consequently rotate the second gear 120. When 130 the rack bar has reached its fully raised posi-

tion, the arm or hook 99 of the plunger seats in the notch 125 of the gear 123 to prevent reverse movement of the gears and rack bar until the plunger is released. In the meantime, the guide pin 95 of the plunger has engaged the swinging closure 127, opening the same and permitting the coin to drop into the main body or coin receptacle of the bank. A suitable key may now be inserted 10 through any of the aligned openings to wind or set either the clock or the alarm. When this is done, the release of the plunger will permit the raising of the same by the spring 98 to release the gear 123 when the springs 15 117 will force the rack bar to lowered position, this movement of the rack bar of course returning the gears 120 and 123 to normal position, thereby cutting off all access to the clock until another coin has been inserted in 20 the slot.

When the bank is to be opened for the removal of the coins contained in the coin receptacle, the proper key is inserted through the opening 55 and turned to swing the 25 tumblers 60 and so actuate the locking bar 58 to free it from the shoulder 36 when the plug lock 53 may be drawn from the end of the casing 31. The key 49 is then inserted in the end of the casing and engaged with the 30 reduced terminal 47 of the post 37 and with the pin 52 when the key is turned to act through the head 39 and arms 43 to release the hooks 24. The inner casing or coin receptacle may then be removed by pulling upon 35 the key which is held against disengagement by the pin 52.

When the coins have been removed, the coin receptacle or removable casing may be replaced, the hooks 24 automatically engaging 40 with the hooks 27 to lock the same in place, after which the plug lock may be applied.

It will of course be understood that the bank, above described, is operable only with 45 a certain specific coin, preferably a ten cent piece.

Having thus described the invention, what is claimed as new is:

1. A coin controlled mechanism, including 50 a closed casing provided with a coin slot and a plurality of openings, means for normally preventing access to said casing through the openings, a rack bar movable in the casing over certain of said openings of the casing, gears meshing with the rack bar and mounted between the other openings, said rack bar and gears being provided with openings which in certain positions of the rack bar and gears register with the openings of the casing, and 55 coin controlled means for actuating one of said gears.

2. A coin controlled mechanism, including 60 a closed casing provided with a coin slot and an opening, a coin chute formed in the casing, a rotatably mounted gear extending into

the coin chute with a tooth in position to engage a coin passing therethrough, and a plunger adapted to engage the coin and force the same past the gear, said forcing of the coin partially rotating the gear. 70

3. A coin controlled mechanism, including a closed casing provided with a coin slot and a plurality of openings, a coin chute, spaced gears rotatable in the casing, one of said gears extending into the chute, said gear being without teeth for a portion of its circumference, a rack bar having teeth meshing with the teeth of the gears, said gears and rack bar being provided with openings which, in one position of the gears and rack bar, register with the openings of the casing, said gear within the chute being adapted to block a coin passing through the same, and a plunger adapted to engage the coin so blocked and force the same past the gear, 80 said forcing of the coin turning the gear. 85

4. A coin controlled mechanism, including a closed casing provided with a coin slot and an opening, means including a rotatable gear for preventing access to the 90 casing through the opening, coin controlled means including a plunger for rotating said gear to permit access to the casing through the opening, and means co-acting between the gear and plunger to lock the 95 gear against counter-rotation.

5. A coin controlled mechanism, including a closed casing provided with a coin slot and an opening, means including a gear provided with a radial notch for preventing 100 access to the casing through the opening, coin controlled means including a plunger for rotating said gear to permit access to the casing, and an arm carried by the plunger and adapted to seat in the notch of the 105 gear to prevent counter-rotation of the gear.

6. A coin controlled mechanism, including a closed casing provided with a coin slot and a plurality of openings, a plate positioned within the casing and provided with 110 registering openings, a pin extending from said plate, a rack bar mounted for reciprocation on said pin, means for normally holding said rack bar in lowered position, said rack bar being provided with openings 115 which, in raised position of the rack bar, register with certain openings in the plate, a gear meshing with the rack bar and provided with an opening which, in raised position of the rack bar, registers with an 120 opening in the plate, a coin chute, a second gear extending by one edge within the chute and meshing with the rack bar, said second gear having an opening which, in raised position of the rack bar, registers with an 125 opening in the plate and also a radially extending notch, that portion of the gear between the notch and the chute being formed without teeth, a plunger forming one wall of the chute and having a stud projecting 130

through the chute in position to engage a coin, and an arm carried by the plunger and adapted to seat in the notch of the second mentioned gear when the rack bar is in raised position.

7. A coin controlled mechanism, including a closed casing provided with a coin slot and a plurality of openings, a vertically movable rack bar mounted within the casing, springs for normally holding said rack bar in lowered position, gears meshing with the rack bar, coin controlled means including a plunger for rotating one of said gears to raise the rack bar, said rack bar and gears being provided with openings which register with the openings of the casing when the rack bar is in raised position, and means carried by the plunger for locking the gears against counter-rotation.
- 10 8. A coin controlled mechanism, including a closed casing provided with a coin slot and a plurality of openings, a coin chute within the casing, a plunger movable over

said chute and forming one wall thereof, a gear extending within the chute in position 25 to block the passage of a coin, a stud extending from the plunger in position to engage the coin and force the same by the gear upon the depression of the plunger, said forced movement of the coin rotating the 30 gear, a rack bar meshing with said gear, a second gear meshing with the rack bar, said gears and rack bar being provided with openings which, in the turned position of the first mentioned gear, register with the 35 openings of the casing, and means co-acting with the rack bar to return the rack bar and gears to normal position upon the release of the plunger.

In testimony whereof I affix my signature in presence of two witnesses.
